UNITED STATES PATENT OFFICE.

WINSOR MOWRY, OF BRISTOL, RHODE ISLAND.

DESIGN FOR A CABINET.

SPECIFICATION forming part of Design No. 22,707, dated August 15, 1893.

Application filed July 14, 1893. Serial No. 480,535. Term of patent 14 years.

To all whom it may concern:

Be it known that I, WINSOR MOWRY, a citizen of the United States, residing at Bristol, in the county of Bristol and State of Rhode Island, have invented and produced a new and original Design for a Furniture Cabinet, of which the following is a specification, reference being had to the accompanying drawings, forming a part thereof.

10 Figure 1. represents a front elevation of a sideboard cabinet, showing my design. Fig. 2. represents a side elevation of the same. Fig. 3. represents a horizontal section taken in the line 3. 3. of Figs. 1. and 2.

15 The leading feature of my design consists of the cornice of the cabinet, the side wings, and the corner shelves between the side wings and the sides of the cabinet.

In the drawings, A represents the table of

a sideboard, and B. the cabinet, the said cabinet being provided with a cornice C, embracing the moldings *a* and *b*, the dentils *c*, the modillions *d* the fascia *h*, and the cyma-recta molding *e*; the said cornice starting from the side wings *f. f.* of the cabinet, and extending along the sides, and across the front of the same, the corner spaces at the sides between the cabinet and the wings, being filled in with the corner shelves *g. g.* thus forming a new and original design for a furniture cabinet. 3

What I claim is—

The design for a furniture cabinet, herein shown and described.

WINSOR MOWRY.
